corporation of Delaware

Application July 9, 1949, Serial No. 103,892

7 Claims. (Cl. 93—37)

1

This invention relates to mechanism for preliminarily breaking cartons of card board or similar material along lines on which they are to be subsequently folded in order to facilitate the subsequent folding operation. Particularly embodiments of this invention are designed to operate upon partially cut out portions or sections of blanks which are left attached at one end and are displaced from the plane of the adjacent portions of the blank about that end as a hinge in the final erecting operation on the carton.

An example of such partially cut out portions is separator wall members or portions, as in the cells of certain types of egg cartons, and the invention will be described and illustrated as applied to such egg cell structures, although it will be understood that with suitable die elements the invention is applicable to various types of blanks.

For the particular egg carton which is to be used to illustrate the invention and which is of the self locking type, the blank is cut to form a continuous series of wall portions which are turned down to form spaced separators and are connected to the blank body only at their top corners by small triangular pieces. As a preliminary to the erecting operation it is necessary to bend these separator wall portions out of the plane of the blank sufficiently to break the material along the eventual hinge line. After the preliminary breaking operations, the egg cell walls will return to their original position, and may be aided in so doing by suitable guides. The carton is then glued and folded flat, ready for later erection and filling.

The breaking of these separator wall portions has heretofore been done by the use of a punch press. An object of this invention is to provide prebreaker means which will operate during the continuous movement of the blanks. Another object is to provide such means which will be readily adaptable for operation upon various size blanks. Other objects are rapidity as well as accuracy of operation, simplicity and inexpensiveness of construction, economy in size and general reliability in performance. Numerous other objects will appear from the description of the illustrated construction.

In accordance with this invention, the breaking is done by co-acting upper and lower breaker wheels between which the egg cell separator wall zone of the blanks is passed. The peripheries are provided with complementary dies corresponding in number with the egg cell separator

walls. The blanks are fed on to a traveling conveyor moving at the peripheral speed of the dies, and are spaced by lugs so that the dies come into register progressively with the partially cut out wall sections. The dies are constructed to provide a support or backing for the blank about the outlines of the sections as the dies engage, and so as to decrease the displacement of the sections from maximum at their free ends to zero at their hinged ends, and thus avoid tearing the wall sections.

The feeding of the blanks is done by feeding wheels, preferably two pairs, and while either bottom or top feed may be used, top feed is best suited to the general design of the illustrated apparatus. In accordance with the invention, one of the feed wheels, preferably the top wheel of each pair if two pairs are used, is provided on its periphery with one or more friction blocks which operate successively to remove the top blank from the feathered out stack on an inclined feed table and bring it into the bite between the feed wheels. The rotation of the feed wheels propels the blank on to supports immediately above the traveling conveyor, where it is checked until a lug comes to engage it and advance it through the region of the breaker wheels.

The number and hence the angular spacing of the friction blocks are varied in accordance with the length of the blanks, and the number and disposition of the dies on the breaker wheels are adjusted to accord with those of the friction blocks, and the lugs on the conveyor are correspondingly set so that each blank comes into proper relation with the dies on the breaker wheels.

The invention also contemplates suitable side guides for the edges of the blanks, and suitable longitudinal supports where needed for the blanks, as well as suitable hold down means for the blanks overlying the supports.

Other novel features of construction will appear from the following description of the mechanism illustrated in the accompanying drawings in which

Fig. 1 is a side view of the apparatus including a portion of the feed table with blanks thereon and a portion of the folding and gluing machine to which the present apparatus delivers.

Fig. 1A is a plan of a blank as it comes from the cutter and on which the present machine is designed to operate.

Fig. 1B is a section of the same on the line 1B—1B of Fig. 1A.

Fig. 1C is a plan of the blank after it has passed through the prebreaker.

Fig. 1D is a section of the same on the line 1D—1D of Fig. 1C, the wall sections being shown at their maximum displacement and before the pressure has been removed and they have been allowed to spring back.

Fig. 1E is a plan of the blank after the gluing and a partial folding operation.

Fig. 1F is a section of the completely folded and glued blank, the internal spacing being somewhat exaggerated for the sake of clarity.

Fig. 1G is a perspective of a section of the carton set up and ready for filling.

Fig. 2 is a diagrammatic view in perspective of the principal working parts of the machine.

Fig. 3 is a transverse sectional elevation on line 3—3 of Fig. 2.

Fig. 4 is a transverse sectional elevation on line 4—4 of Fig. 2.

Fig. 5 is an enlarged longitudinal sectional elevation of the feeding end of the machine on the line 5—5 of Fig. 3.

Fig. 6 is a similar sectional elevation of the breaker wheel portion of the machine on line 6—6 of Fig. 4.

Fig. 7 is a plan of a fragmentary portion of a blank and section of the upper breaker wheel dies at the work line showing the contact of the dies and blank.

The general purpose and operation of the machine will be understood from reference to Figs. 1 to 1G. The feeder mechanism is indicated generally by the numeral 10 and the breaker mechanism by the numeral 11. A pile of blanks 12 are disposed on the inclined table 13, being feathered or stepped so that the top blank leads. Picker members on the rotary feeders, as will later be described, successively pick off the top blank and advance it to the feeders which deliver it on to the endless conveyor chain 14 which passes it through the breaker mechanism 11 and thence to the pulling rolls 15 of the gluer and folding section 16.

The blank is shown in Fig. 1A as it comes from the cutter. Near one end there is formed by outline cutting a series of six internal separator or egg cell wall sections of which three numbered 17 are attached at their rear ends in relation to the direction of movement of the blank as indicated by the arrow A, and the other three numbered 18 are reversed. The object is to break the crease or fold line of these six cell walls.

After passing through the breaker section these six walls are broken down from the flat position of Fig. 1B to the angular position of Fig. 1D. The blanks are then caught by the rollers 15 of the gluing and folding section 16, which have a somewhat greater speed than the conveyor and pull the blank away from the pushing lugs on the conveyor which will later be referred to.

The gluing and folding section turns over the narrow panel 12a and glues it to the middle of panel 12b, the cover 12c folding over on crease 12d.

The flat folded blank thus formed is eventually delivered to another machine where it is erected as shown in Fig. 1G. When closed the cover is self locking, the fingers 12e engaging under the outer triangular pieces 12f by which the separator walls are connected to the blank body.

The machine has two side frame members 17 and 18 which provide bearings for four main shafts, two for the feeder and two for the breaker

mechanism. The general relationship of these shafts and of the wheels and other parts carried thereby is shown diagrammatically in Fig. 2.

Of the two feeder wheel shafts, the lower shaft 19 bears in the side frames and the upper shaft 20 bears in brackets 21 on the top of the side frames. The lower shaft 19 has two spaced feed wheels 22 and 23 and the upper shaft 20 has two feed wheels 24 and 25 which cooperate with wheels 22 and 23, respectively.

Of the two shafts of the breaker section, the lower shaft 26 bears in the side frames and the upper shaft 27 bears in brackets 28 on top of the side frames. Secured on these shafts are a pair of cooperative breaker wheels 29 and 30, respectively.

Power is applied to the lower feed wheel shaft 19 and the other moving parts are driven therefrom. Shafts 19 and 20 are geared together by gears 31 and 32. The lower feed wheels 22 and 23 are smaller than the upper feed wheels 24 and 25, and the ratio of the gears 31 and 32 is such that the peripheral speed of the feed wheels is the same.

The lower breaker wheel shaft 26 is driven from shaft 19 by a sprocket chain 33 which connects sprocket wheel 34 on shaft 19 with sprocket wheel 35 on shaft 26. Breaker wheel shafts 26 and 27 are geared together in a one to one ratio by gear wheels 36 and 37, and the ratio of sprocket wheels 34 and 35 is such that shafts 26 and 27 have the same rate as that of the upper feed wheel shaft 28. Since the breaker wheels 29 and 30 have the same diameter as the upper feed wheels 24 and 25, it follows that the feed wheels and the breaker wheels all have the same peripheral speed.

As shown, there are two conveyor chains 14 which run over idler sprockets 38 on the lower feed wheel shaft 19, the disposition being such that the feed wheels 22 and 24 are between the chains and the feed wheels 23 and 25 are outside the chains.

From the idlers 38 the chains run horizontally over sprockets 39 fixed on shaft 40 which bears in the side frames at the rear end of the machine, and thence down over idlers 41 on shaft 42 and thence forward horizontally over idlers 43 on shaft 44 and thence up to the sprockets 38. The shaft 40 is driven from the shaft 19 through a pair of intermediate sprockets the ratio of which is readily variable in order to synchronize the conveyor speed with the peripheral speed of the breaker wheels.

The changeable double sprocket member consists of sprockets 45 and 46 loosely bearing on stud 47 on the side frame member 18 substantially midway between the shafts 19 and 40. A sprocket chain 48 runs over a sprocket 49 fixed on the shaft 19 near its end opposite the gearing drive, and over the sprocket 46. Sprocket 45 is secured to sprocket 46 so as to turn therewith, and a chain 50 runs over sprocket 45 and over sprocket 51 fixed on shaft 40.

Over the upper feed wheels 24 and 25 are brushes 52 and 53, respectively, on shaft 54 the bearings for which are supported by suitable brackets attached to the frame of the machine, and which is driven by belt 55 which runs over pulley 56 on shaft 20 and pulley 57 on shaft 54.

For protective purposes, the gearing on the right end of the shafts and the sprocket and chain drive from shaft 19 to shaft 26 are shown as enclosed within a housing 58 which may have an inner cover plate 59. The brackets 21 which

support the bearings for the upper feed wheel shaft 20 are adjustable vertically, as indicated in Fig. 3, in order to control the spacing between the upper and lower feed wheels according to the thickness of the blanks.

The lower feed wheels 22 and 23 are rubber faced. The upper feed wheels have a series of four peripheral cavities 60 each of which is adapted to receive a rubber faced block 61 or a dummy filler block 62. Two of the cavities are 180° apart and the other two are 120° apart and 120° each from one of the first two cavities. The rubber faced blocks 61 are friction blocks that pick off the top blank from the stack on the table 13 as they pass by. Hence the upper wheels can be made to pick off one, two or three blanks for each rotation, depending on the number of picker blocks used, which in turn depends upon the length of the blanks. It is shown in Fig. 5 with two picker or stripper blocks and with that setting will feed two blanks with each rotation.

As shown in Fig. 5, the blanks in the stack on the feed table are feathered out or shingled with the top blank in contact with the upper feeder wheels and the blanks immediately underneath successively engaging an adjustable rubber faced retarder block 63, which is set so as to permit the feeding of only one blank at a time. The upper feeder wheels turn clockwise as seen in Fig. 5, and the top block 61 will strip off the top blank from the stack as it comes around and feed it between the feeder wheels, the lower block 61 will strip off the next blank, and so on.

The blank is guided by edge guides 64 and 65 after leaving the feed wheels, and rests intermediate its edges on chain shields 66, on longitudinal supports 67 disposed between the chains and on support 68 outside the feed wheels 23 and 25. Adjustably mounted on a cross shaft 69 supported by bracket 70 from the frame of the machine are hold down means overlying the blanks on the supports 66, 67 and 68, consisting of an adjustable bar 71 over the left hand shield 66, a rod 72 over the right hand shield 66 and two rods 73 over the support 68.

Also overlying the supports 67 is a retarder 74 on the end of curved rod 75 carried by the adjustable bracket on shaft 69. The function of this retarder 74 is to check the movement of the blanks as they leave the feeder wheels and cause them to await the arrival of engaging means on the conveyor chains which are so adjusted as to time the feed of the blanks properly into the breaker.

For this purpose, the chains are provided with spaced lugs 76 which are relatively aligned on the two chains and are variable in number and setting so as to take care of single, double or triple feed of blanks for each rotation of the feed wheels. For this purpose, the chains are provided with pin groups which may be spaced at intervals of fourteen, twenty-one and forty-two inches so that the detachable lugs 76 may be fastened thereto, the fourteen inch spacing being for triple feed, the twenty-one inch spacing being for double feed and the forty-two inch spacing being for single feed.

The support 68 is in line with the breaker wheels 29 and 30 which are disposed so as to receive the separator wall zone of the blanks between them. The wheels are equipped with mating or complementary dies which coact to break downwardly the sections 17 and 18 of the blanks. There are two dies in each of the upper and lower wheels, disposed side by side, for each separator wall

section, and since there are six separators in each blank, there are altogether twelve dies on each wheel for each group of dies, that is, for each blank. There will be one group of dies for each blank fed for each rotation of the feed and breaker wheels, and there are, therefore, two dies groups spaced 180° in the construction as shown.

The upper breaker dies 77 are external dies, that is, they act as plungers, and the lower breaker dies 78 are internal, that is, they are cups and receive the plungers, the coating dies coming successively into register as the wheels turn. The die elements are in each wheel secured to circumferentially adjustable blocks on the respective wheel periphery. The two upper die elements 77a and 77b of each pair coact with the registering lower die elements 78a and 78b, respectively, and the lower die elements are partially surrounded by a rim 79 which bears on the underside of the blank around each cut and provides a support against which the breaking pressure is applied.

The adjustable block 80 for each upper die pair is held to the rim of the wheel 30, by cap screws threaded in a nut 81 which is retained in a dovetail slot in the rim and when loosened permits circumferential adjustment of the dies. In this way the breaker dies can be clamped in any desired position on the wheel. The die elements are attached to the blocks 80 by screws and dowel pins, as shown in Figs. 4 and 6. The lower die elements 78a and 78b of each pair of breakers are similarly attached to similar adjustable blocks 82.

The contour of the upper breaker dies 77a and 77b is such as to avoid tearing the separator walls 17 and 18 at their attached ends. For this purpose the upper dies are rounded off or radially relieved at the ends which engage the attached ends of the separator walls. This is shown in the sectional and side views of Fig. 6. Since the wall members 17 and 18 are relatively reversed, the leading three pairs of dies 77b are reversed relative to the trailing three pairs, the first three being rounded off or relieved at their rear end and the latter three being relieved at their front end. The rims 79 of the first three lower die pairs are, consequently, reversed with respect to the last three of each group. In both groups the two sets of three are slightly spaced as required by the blank.

In the operation of the machine as shown, two blanks are fed and two are broken by each revolution of the feeder and breaker wheels. The operator takes a number of blanks and feathers or fans them out in a step-like manner so that the upper blank is farthest forward on the pile and the blanks underneath extend backward in even progression with the sides of the blanks in line. The pile of feathered out blanks is then placed on the feed table with the upper blank resting against the surfaces of the upper feed wheels. A sheet of tin or other smooth material is secured on top of the inclined feed boards to provide a surface on which the blanks will slide down freely against the feed wheels to permit continuous feeding.

The first friction blocks 61 to engage the top blank in the rotation of the feed wheels pull a blank through the gap at the retarder and advance it to the bite of the feed wheels. When the trailing edge of the blank has passed through between the feed wheels, the forward progress of the blank ceases momentarily until the lugs on the conveyor chains contact the rear edge of the blank and push it through between the breaker

wheels. The dies coat to break down the separator walls as the blank passes through, after which it is caught by the pull rollers of the gluing and folding section.

It will be understood that while the specific construction shown is presented as a satisfactory embodiment of the invention, it may in many respects be otherwise embodied without departing from the principle and scope of the invention as defined in the following claims.

We claim:

1. For carton blanks having a linear series of cut-out separator wall portions each attached to the blank on one end, prebreaker mechanism for angularly bending the separator wall portions out of the plane of the blank and preliminarily breaking the material of the blank on the line of bend of each wall portion, said mechanism comprising side guides for blanks, two parallel conveyor chains between the guides, spaced lugs similarly disposed on the two chains, a pair of cooperative feed wheels disposed between the chains in position to receive and deliver blanks on to the chains with their edges in the side guides, hold down means over the path of the blank to hold the blanks on the chains, separate retarder means over the chains operative to check the momentum of blanks delivered on to the chains, a pair of cooperative breaker wheels disposed in a plane outside the chains in position to receive the separator wall portions of the blanks between them, registering complementary dies on the breaker wheel peripheries operative to engage the wall portions successively and bend them about their attached ends, means to drive the chains continuously in synchronism, and means to drive the feed and breaker wheels continuously.

2. For carton blanks having a linear series of cut-out separator wall portions each attached to the blank on one end, prebreaker mechanism for angularly bending the separator wall portions out of the plane of the blank and preliminarily breaking the material of the blank on the line of bend of each wall portion, said mechanism comprising side guides for blanks, two parallel conveyor chains between the guides, spaced lugs similarly disposed on the two chains, a pair of cooperative feed wheels disposed between the chains in position to receive and deliver blanks on to the chains with their edges in the side guides, hold down means over the path of the blank to hold the blanks on the chains, separate retarder means over the chains operative to check the momentum of blanks delivered on to the chains, a pair of cooperative breaker wheels disposed in a plane outside the chains in position to receive the separator wall portions of the blanks between them, registering complementary dies on the breaker wheel peripheries operative to engage the wall portions successively and bend them about their attached ends, interconnected means to drive the feed and breaker wheels continuously at the same peripheral speed, and means to drive the chains continuously in synchronism at a speed equal to said peripheral speed.

3. In a prebreaker mechanism as claimed in claim 2, circumferentially adjustable holding means for the dies on the peripheries of the breaker wheels, and securing means for the lugs

disposed along the chains in proper spacing to permit selective positioning of the lugs in timed relation to the circumferential positions of the dies.

5 4. A prebreaker mechanism as claimed in claim 2 in which the dies on one of the breaker wheels are cups the upstanding wall of which is shaped to engage the blank about the cut edge of each separator wall portion and the dies on the other breaker wheel are protruding blocks shaped to enter the cups.

10 5. A prebreaker mechanism as claimed in claim 2 in which the dies on the lower breaker wheel are cups and the dies on the upper breaker wheel are protruding blocks having a peripheral contour with the portion which engages the attached end of the separator wall portions substantially radially relieved.

15 6. A prebreaker mechanism as claimed in claim 2 in which in each series of dies half of the die blocks have the contours of their engaging faces shaped with their trailing portions substantially radially relieved and the other half have the leading portions of their engaging faces substantially radially relieved.

20 7. For carton blanks having a linear series of cut-out separator wall portions each attached to the blank on one end, prebreaker mechanism for angularly bending the separator wall portions out of the plane of the blank and preliminarily breaking the material of the blank on the line of bend of each wall portion, said mechanism comprising side guides for blanks, two parallel conveyor chains between the guides, adjustable spaced lugs similarly disposed on the two chains, a longitudinally extending blank support between the chains, hold down means for blanks extending over the support, a pair of cooperative feeding wheels disposed in position to receive 25 and deliver blanks on to the chains and support underneath the hold down means, circumferentially adjustable blank picker means on the periphery of one of the feeding wheels, a pair of cooperative breaker wheels disposed in a plane 30 outside the chains in position to receive the separator wall portions of the blanks between them, a longitudinally extending blank support in line with the breaker wheels, hold down means for blanks extending over the latter support, registering complementary dies adjustably disposed 35 on the breaker wheel peripheries operative to engage the wall portions successively and bend them about their attached ends, means to drive the feed and breaker wheels continuously at the same peripheral speed, and means to drive the chains continuously in synchronism at the said peripheral speed.
